SCREEN FRAME

Louis J. Milone, Livingston, N. J., assignor to
 Orange Screen Company, Maplewood, N. J., a
 corporation of New Jersey

Application February 24, 1931. Serial No. 517,723

2 Claims. (Cl. 156—14)

This invention relates to screens or the like, and aims to provide certain improvements therein.

The principal object of the present invention is to provide a frame adapted for use in the construction of screens, sashes or other similar devices. To this end the invention introduces a rail or stile of a novel cross-section which is particularly adapted for the manufacture of such screen frames, and has the capacity of being useful in connection with the construction of frames of different types and kinds.

In the manufacture of metallic screen frames, the product and process set forth in the patents 15 to Otto, Reissue No. 16,148 and No. 1,596,507 have been considerably utilized. This product is a section of aluminum or aluminum alloy extruded to the precise cross-section desired for the frame. A light and very rigid structure is attained by 20 the use of these sections welded or otherwise made into a substantially integral joint at the corners.

The object of the present invention is to provide a frame of this general type which when used for screens will include a screen channel in which 25 the edges of the wire cloth are anchored. The construction is such, however, that I secure a maximum stiffness and rigidity with the least possible weight of metal and in the cheapest possible manner. Not only is this accomplished, 30 but I provide a cross-section which fits the frame for varied fields of usefulness, as will be herein-after more fully set forth.

The invention also includes devices in which such sections are utilized with the attendant features.

Referring to the drawings, which illustrate several forms of the invention,—

Figure 1 is a perspective view, partly in section, of the upper portion of a window ventilator, having at its top a screen constructed mainly of the extruded aluminum sections provided by this invention.

Fig. 1^a is a similar perspective view of a strip utilized at several parts of Fig. 1.

Fig. 2 is a perspective view, partly in section, of a form of rails and stiles of a slightly modified cross-section.

Fig. 3 is a perspective view of an expandible and contractible window screen constructed of material of the same cross-section as that used in Fig. 1.

Fig. 4 is a similar perspective view, partly in section, and constructed of the material of the two cross-sections illustrated in Figs. 1 and 2.

Fig. 5 is a perspective view, partly in section,

of a key such as is utilized in the constructions of Figs. 3 and 4.

Referring first to Figs. 1 and 1^a I have in these figures illustrated a window ventilator, comprising metallic side pieces A formed of sheet metal 60 (one of which is shown), a glass or other front plate B, having side frames B', adapted to fit between the two side pieces, being held in place by flanges, such as C, and a screen D hinged to the frame pieces B'. 65

The screen D is constructed of a frame E and wire netting F, although for the latter may be substituted any desired material.

An important feature of the invention is the construction of the rails and stiles of the screen 70 metal having a novel cross-section, some modifications of which are shown in the drawings. This metal is usually an extruded aluminum alloy, and if a wire cloth or other similar material is to be used extending across the frame, the 75 cross-section is such as to provide a screen-retaining channel G in which the edges of the screen are located, and in which they are held by a suitable anchor H of any desired construction. I prefer to so construct the screen-retaining 80 channel that it is undercut on its edge, as shown at I, and preferably also on its opposite side, as shown at J, and I also prefer to construct the anchor as an elastic U-shaped member adapted to pass through the restricted slot formed by 85 undercutting the screen channel and expanding into the undercut portions, as shown. This construction I have found makes a very firm and secure connection between the screen and the rails and stiles without the use of undue pressure. 90

According to the present invention the extruded metal is provided with one or more slots K—L. These slots are preferably two in number, and are also undercut, as shown. The precise location of the slots may be varied, thus in Figure 95 1 the slot K is arranged so that it opens at what may be termed the outside of the screen section; that is to say, the side which is opposite the side lying next to the wire cloth. In this figure also the slot L opens downwardly in 100 the same direction as the screen channel.

In Figure 2, however, the slot K' opens upwardly in an opposite direction from that of the screen channel, while the slot L' is at the outside of the frame, but opposite the opening 105 of the screen channel instead of opposite its closed side, as is the case in the construction shown in Figure 1. To describe the construction in another way, the two modifications are identical except that the screen channel is lo- 110

cated in Figure 2 on the opposite side from that in which it is formed in Figure 1. In both instances there is a channel K or L opening edge-wise of the strip and a similar channel opening 5 to the top or bottom.

These sections are of great utility. Even with a large screen channel they provide a frame which is very stiff and rigid in proportion to its size and weight. For instance, I can provide 10 a screen constructed of material having an overall width and depth of approximately five-eighths of an inch, which when welded at the corners is amply strong and rigid for frames of considerable size.

15 Furthermore, the channels J and K are exceedingly useful for a number of purposes,—thus in Figure 1 the channel K is utilized to engage and hold a rubber or other flexible strip, such as M, by means of which the hinged door of 20 the ventilator makes a substantially dust-tight fit with the lower sash N of the window. So also on the opposite side of the screen door the channel L is utilized for a similar strip M which closes the opening between the lower face 25 of the screen and the top of the glass front E.

In Figure 3 I have shown a construction of adjustable window screen in which there are two sliding frames P and Q, each of which is formed of aluminum of the cross-section shown in Figure 1. These two screens may be easily adapted to slide together by the provision of a length of metal of dumb-bell cross section, such as shown in Fig. 5, at R, each of the edges of the metal entering one of the enlarged portions of the slots 30 L which in Fig. 3 are arranged face to face. This provides a sliding adjustable screen in which the two screen cloths lie adjacent to each other.

35 In Fig. 4 I have shown a similar construction of sliding adjustable screen in which both cross-sections are used, so that the actual screen cloths are spaced apart. This would ordinarily produce a space for the ingress of insects, etc. between the two screens, but it will be noted that the upright section of the screen Q' which 40 is omitted from the drawings will lie alongside of the screen cloth of the screen P' all the way from the bottom to the top, thereby preventing 45 ingress of insects or the like.

50 When used, as shown in Figs. 3 and 4, the upper and lower members of the frame may be provided with weather-stripping designed to contact with the frame of the window and the under side of the sash if desired. Such weather-

stripping may be of the general character shown at M in Fig. 1^e. The same is true when members of the particular cross-section provided by my invention are utilized to construct ordinary sliding or hinged window sashes, doors or the like. 50 So also if it is desired to utilize the channels K and L, or either of them, to secure sheets of glass or other material, the latter may be cemented in the channels or by a slight pressing or rolling operation the lips of the channels may be compressed about such sheets. 85

The screen channel may, of course, be omitted where desired, or may be utilized if suitably formed to engage or anchor other materials than the netting shown. 90

95 While I have shown and described several forms of the invention, it will be understood that I do not wish to be limited thereto, as various changes may be made therein without departing from the invention.

What I claim is:

1. A section for screens or the like, comprising a strip of metal of general rectangular cross section, and having in one face thereof a longitudinal channel of considerable cross sectional 100 dimensions adapted to receive the edge of a screen or the like, and having at least two channels of considerably smaller cross section leading from the faces of the section, said last-named channels having enlarged inner portions 105 and restricted openings to the exterior, all of said channels together forming a large portion of the total cross section of the metal.

2. A section for screens or the like, comprising an extruded metal containing a high proportion of aluminum, said section being of general rectangular cross section, and being provided on one side with a screen-retaining channel of considerable dimensions adapted to receive not only the screen fabric but also an anchor 110 for the screen fabric, one side of said section which is adapted to face inwardly in a screen being ungrooved, and its companion parallel surface being provided with a relatively smaller groove having an enlarged interior and a restricted opening, and a second groove similar to said last-named groove arranged in one of the faces of the screen section, a cross section of the metal being largely occupied by the area of the grooves, and the metallic wall defining the 120 grooves being generally of approximately the same thickness throughout the cross section.
